UNITED STATES PATENT OFFICE.

DAYTON S. HALLOWAY, OF ALBANY, OREGON.

MILK-BOTTLE LOCK.

Application filed August 23, 1927. Serial No. 214,868.

The present invention relates to an improved device constructed to provide what is believed to be an improved milk bottle holder.

5 Briefly, the invention has reference to a closed top box, a bottom having slots for passage of the milk bottles and novel means arranged intermediate the cover and bottom for supporting and retaining a milk bottle 10 in place.

The alleged novelty is based upon the improved details and their relative arrangement, and particularly, means for suspending and retaining the bottles in place in a 15 manner to frustrate removal by unauthorized persons.

The details will become more readily apparent from the following detailed description and concluding claims.

20 In the drawings:—

Figure 1 is a bottom perspective view of a holder constructed in accordance with the invention.

Figure 2 is a top plan view with the cover 25 removed.

Figure 3 is a central longitudinal section through the structure.

Figures 4 and 5 are enlarged cross sectional views taken approximately on the planes 30 of the lines 4—4 and 5—5 respectively of Figure 3.

Referring now to the drawings by reference numerals it will be observed that the box is generally designated by the reference character 6. This is of general rectangular configuration and as before stated is closed at its top, by a removable cover plate 7 being provided for coverage. A raised bottom 8 is provided in the box and this is 35 formed adjacent its opposite ends with elongated openings 9 and 10, respectively. These openings are of general ovate configuration as shown better in Figure 1.

Rigidly mounted in the box is a horizontal 40 partition plate 10 which is provided above the openings 9 with complementary slots 11 and 12, respectively. It will be noted that the outer end portions of these slots 11 and 12 are enlarged and are of circular configuration, being formed on their marginal

edges with radiating notches 13 forming keeper seats. The restricted end portions of these slots 11 are disposed toward each other as indicated in Figure 2. Struck up from the partition plates near the margins are tongues 14 bent to form guides for a slide 15. The slide is formed with circular bottle neck receiving holes 16 and 17, respectively. The holes are of a diameter to permit free passage of the bottle neck upwardly therethrough. Struck up around the marginal portions of the holes 17 are small tongues 18 arranged in pairs to provide pivotal mountings for a plurality of radially disposed latches 19. The latches are of the configuration represented plainly in Figures 4 and 5, the base portions being rounded and adapted to work through the aforesaid keeper, notches, or seats 13. Incidentally these latches are so pivoted that they gravitate 70 automatically to locking position which position is shown in Figures 3 and 5. However, they are capable of being swung upwardly to the position represented in Figure 4 which is releasing position. This 75 must be done with the use of a bottle however. In connection with the hole 16 it will be observed that an arch 20 is located over this, this arch carrying a back member 21 which is in turn provided with a multiplicity of depending pins or spurs 22 which 80 extend down through the opening to the point represented in Figure 3. The back member 21 is held in place by an elongated bolt 23, which extends down and 85 beyond the points of the pin to serve as a stock and guard.

The device is used as follows:—Assuming that the slide 15 is in the position represented in Figures 2 and 3, for instance, it 90 will be seen that the latches 19 surrounding the hole 16 are in elevated position, while those surrounding the hole 17 are in depending locking position. In other words, the rounded base portions of the latches are then 95 dropped down into the keeper seats 13. As it is now desired to insert a full bottle of milk, the milkman simply places the bottle upwardly through the opening 10 at the right of the base plate 8. As it is elevated 100

the bead at the top strikes the depending end portions of the latches and serves to swing them upwardly to the position shown in Figure 4 whereupon the slide is released and can be shifted over to the left. At this time the bottle neck is extending through the hole 17 as well as the enlarged portion of the slot 12. However, by exerting sufficient force the bottle together with its slide are shifted over to the left, bringing the bottle neck to the restricted portion of the slot 12 whereupon it is retained against displacement. At the same time the bottle is received in this restricted portion, the latches surrounding the opening 16 have become aligned with the keeper seats 13 in the enlarged portion of the slot 11. Hence it may drop by gravity down into locking position, serving to hold the bottle against removal. Of course, to take the bottle out it is necessary for the housewife to take an empty bottle and insert it upwardly through the opening 9, thence through the slot 12 and the opening 16. This raises the latches again and permits the slide to be shifted to the original position for reception of a full bottle. Incidentally the deepening pins 22 tend to prevent persons from placing the fingers upwardly to lift the latches and to shift the plate in an unauthorized manner to remove the full bottle of milk. It will be noted however that the bolt 23 serves to stop in the engagement member so that if an empty bottle with a cap on it is inadvertently inserted, it will strike this bolt and thus force the cap into the bottle and prevent cap from sticking to sharp prongs 22. The full bottle is always on the right therefore no guard is necessary on that end. The projection 23 referred to as a bolt also acts as a guard in protecting sharp prongs 22 in case an attempt to open the lock with a stick is made. In dotted lines in Figure 3 I have shown how an empty bottle is arranged in place for removal by the milkman after he has placed a full bottle in the opposite end of the structure and shifted to slide as before described.

It is thought that by considering the detailed description in connection with the drawings a clear understanding of the construction and operation and efficiency of the device will be had. Therefore, a more lengthy description is believed unnecessary.

While the preferred embodiment of the invention has been detailed and specifically described, it is to be understood that minor changes in shape, size, and rearrangement of parts coming within the field of invention claimed may be resorted to if desired.

Having thus described the invention, what I claim as new is:—

1. In a milk bottle lock and holder of the class described, a box having a bottom provided with elongated openings for passage

of a milk bottle, a partition plate in said box disposed in spaced parallelism with said bottom and formed with key-hole shaped slots in vertical alinement with said openings to permit a milk bottle to be inserted through the openings and passed upwardly and into the enlarged end portions of the slots and then shifted longitudinally into the restricted portions of the slots whereby it is suspended, and a longitudinally shiftable retaining device on said partition plate cooperable with said slots, said device being provided with holes for passage of the bottle neck. 70 75

2. In a milk bottle holder of the class described, a box provided with a bottom having elongated openings, a horizontal partition plate in said box disposed in spaced parallelism above said bottom and provided with key-hole shaped slots, said slots in turn being formed with notches providing keeper seats, a slide mounted on said partition plate and provided with openings adapted to successively register with the enlarged and restricted portions of said slots, and pivoted gravity lowered latches carried by said slide and receivable in said keeper seats. 80 85 90

3. In a structure of the class described, a closed top box, said box having a bottom provided with longitudinally spaced elongated openings adapted for passage of the neck of a bottle, a horizontal partition plate in said box disposed in vertically spaced parallelism with said bottom, said partition plate having key-hole shaped slots in vertical alinement with said openings, the enlarged end portions of said box being provided with marginal circumferentially spaced radiating notches forming keeper seats, guides carried by the marginal portions of said partition plate, a slide mounted in said guides, said slide being provided with circular holes adapted to register with the opposite end portions in said slots in a successive manner, individual latches pivotally mounted around the marginal portions of the holes in said slide, said latches including arcuate shaped base portions cooperable with said keeper seats, and the free end portions adapted to swing downwardly 95 100 105 110 through said holes and said slots. 115

4. In a structure of the class described, a closed top box, said box having a bottom provided with longitudinally spaced elongated openings adapted for passage of the neck of a bottle, a horizontal partition plate in said box disposed in vertically spaced parallelism with said bottom, said partition plate having key-hole shaped slots in vertical alinement with said openings, the enlarged end portions of said box being provided with marginal circumferentially spaced radiating notches forming keeper seats, guides carried by the marginal portions of said partition plate, a slide mounted 120 125 130

in said guides, said slide being provided with circular holes adapted to register with the opposite end portions in said slots in a successive manner, individual latches pivotally mounted around the marginal portions of the holes in said slide, said latches including arcuate shaped base portions cooperable with

said keeper seats, and the free end portions adapted to swing downwardly through said holes and said slots, and a guard and stop device carried by said slide and disposed over one of said holes. ¹⁰

In testimony whereof I affix my signature.
DAYTON S. HALLOWAY.
